TELEPHONE EAR PIECE

Thomas A. Scanlon, Barrington, R.I.

Application October 21, 1959, Serial No. 58,002

Term of patent 14 years

(Cl. D26—14)

FIG. 1

FIG. 2

FIG. 3

Figure 1 is a perspective view of a telephone ear piece, showing my new design.

Figure 2 is a side elevational view, the opposite side being substantially a mirror image, thereof; and

Figure 3 is a rear elevational view thereof.

I claim:

The ornamental design for a telephone ear piece, as shown and described.
